To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to which it pertains to make and use it, reference being had to the accompanying drawing, which forms part of this specification.

My invention relates to an improvement in designs for cane, umbrella, or parasol handles; and it consists in the configuration which will be more fully described hereinafter, whereby a very beautiful, novel, and attractive design is produced.

The accompanying photographic illustration represents my invention.

A represents the main portion of the handle, which is flattened upon its outer side, and the edges of this flattened portion given any ornamental shape that may be preferred.

The upper end of this handle is bent or turned 25 at a suitable angle, and the sides of this bent portion are provided with spiral grooves, edges, or flanges, as shown. Against the flattened portion of the handle is the figure of a lion standing upon two feet and having 30 the upper portion of his body incased in a coat or garment, and upon the top of his head is placed the representation of a crown. One of the lion's arms is represented as extending down into a side pocket.

Having thus described my invention, I claim—

A design for cane, umbrella, or parasol handles, consisting of the handle having the upper bent end or portion and the representation of a lion formed upon the side of the handle, as shown and described.
